DESIGN FOR A CANDELABRUM OR LIKE ARTICLE

Sidney Weinberg, Philadelphia, Pa., assignor to Stanley G. Levy, Philadelphia, Pa., trading as Levy Bros.

Application October 22, 1940, Serial No. 96,003

Term of patent 3½ years

To all whom it may concern:

Be it known that I, Sidney Weinberg, a citizen of the United States, residing in Philadelphia, county of Philadelphia, State of Pennsylvania, have invented a new, original, and ornamental Design for a Candelabrum or Like Article, of which the following is a specification, reference being had to the accompanying drawing, forming a part thereof, in which the single view is a perspective view of a candelabrum or like article, showing my new design.

I claim:

The ornamental design for a candelabrum or like article, as shown.

SIDNEY WEINBERG.
